US00D420331S

United States Patent [19]

Martin et al.

[11] Patent Number: Des. 420,331

[45] Date of Patent: ** Feb. 8, 2000

[54] ELECTRICAL WIRE TERMINATOR

[75] Inventors: **Demian T. Martin**, Pacifica; **Kendrew Lee**, San Jose, both of Calif.[73] Assignee: **Monster Cable Products, Inc.**, Brisbane, Calif.

[**] Term: 14 Years

[21] Appl. No.: 29/081,436

[22] Filed: Jan. 2, 1998

[51] LOC (7) Cl. 13-03

[52] U.S. Cl. D13/148

[58] Field of Search D13/148; D8/399; 439/877, 882, 884, 860; 411/522, 161

[57] CLAIM

The ornamental design for an electrical wire terminator, as shown.

DESCRIPTION

“A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.”

FIG. 1 is a perspective view of the electrical wire terminator according to the present invention.

FIG. 2 is a bottom view of the electrical wire terminator shown in FIG. 1.

FIG. 3 is a top view of the electrical wire terminator shown in FIG. 1.

FIG. 4 is a left side view of the electrical wire terminator shown in FIG. 1.

FIG. 5 is a right side view of the electrical wire terminator shown in FIG. 1.

FIG. 6 is a front view of the electrical wire terminator shown in FIG. 1; and,

FIG. 7 is a rear view of the electrical wire terminator shown in FIG. 1.
